PAIR OF SUNGLASSES

Jack F. Fleming, Summit, N. J., assignor to Curtiss-Wright Corporation, a corporation of Delaware

Application April 28, 1955, Serial No. 35,719

Term of patent 7 years

(Cl. D57—1)

Fig. 1 is a perspective view of a pair of sunglasses showing my design.

Fig. 2 is a vertical sectional view through the front of the sunglasses on line 2—2 of Fig. 1.

The characteristic features of my design for a pair of sunglasses reside in the protruding ridge portions on the frame of the sunglasses, as shown.

I claim:

The ornamental design for a pair of sunglasses, substantially as shown and described.
